UNITED STATES PATENT OFFICE.

WILLIAM ALEX. WILLIAMSON, OF NEWARK, NEW JERSEY.

DESIGN FOR A PICTURE-HOOK.

SPECIFICATION forming part of Design No. 19,046, dated April 9, 1889.

Application filed March 11, 1889. Serial No. 302,905. Term of patent 14 years.

To all whom it may concern:

Be it known that I, WILLIAM ALEX. WILLIAMSON, a citizen of the United States, residing at Newark, in the county of Essex and State of New Jersey, have invented a new and original Design for a Picture-Hook, of which the following is a specification, reference being had to the accompanying drawings, forming a part thereof.

In the accompanying drawings, Figure 1 is front elevation of my design, and Fig. 2 is side elevation of the same.

As indicated in the views to which reference is made in the above, my design for a picture or a molding hook presents in front elevation two parallel wires, *a* and *a'*, at the top and the bottom of the hook, the wires at the bottom part of the hook being circular or round in cross-section, and flat at the top part of the hook and rectangular in cross-section.

The parallel wires join and form a twist, *b*, which presents the same appearance on all sides, and, as already stated, below and above the twist the wires are parallel and in front elevation form a small loop, *c*.

Above the twist the parallel wires present the appearance of a hook, *a*, when viewed in side elevation, and also the parallel wires below the twist form the hook *c'* when viewed in side elevation, said hook *c'* being much 30 smaller than the upper hook.

I claim—

The design for a picture or molding hook herein shown and described, the same consisting of two parallel wires, *a a'*, twisted at *b* and 35 forming a small loop, *c*, in front elevation, and in side elevation a hook, *a*, above the twist, and flat and rectangular in cross-section, and a hook, *c'*, below the twist and round in cross-section.

In testimony that I claim the invention set forth above I have hereunto set my hand this 40 8th day of March, 1889.

WILLIAM ALEX. WILLIAMSON.
